UNITED STATES PATENT OFFICE.

OLLIE L. LAFFERIOR AND NELSON A. LAFFERIOR, OF ARGYLE, MINNESOTA.

CLOTHES WRINGER.

Application filed October 30, 1922. Serial No. 597,832.

To all whom it may concern:

Be it known that we, OLLIE L. LAFFERIOR and NELSON A. LAFFERIOR, citizens of the United States, residing at Argyle, in the county of Marshall, State of Minnesota, have invented certain new and useful Improvements in Clothes Wringers; and we do hereby declare the following to be a full, clear, and exact description of the invention, such as will enable others skilled in the art to which it appertains to make and use the same.

This invention relates to new and useful improvements in clothes wringers and particularly to clothes wringers used in connection with motor driven washing machines, and especially in connection with the washing machine forming the subject-matter of an application filed October 30, 1922, Serial Number 597,831, as a companion to this present application.

One object of the invention is to provide a wringer which is mounted on the frame of the washing machine, and which can be swung horizontally into different positions with respect to the tub, and which has novel means for maintaining the wringer in such positions.

Another object is to provide novel and improved gearing for driving the wringer, and which gearing is readily and easily shiftable into and out of operation.

Other objects and advantages will be apparent from the following description when taken in connection with the accompanying drawing.

In the drawing:

Figure 1 is a side elevation of the wringer shown in connection with a portion of a washing machine, the wringer being positioned for operation, in connection with the tub.

Figure 2 is a front elevation of the wringer, the casing being broken away to expose the gearing and gear shifting mechanism.

Figure 3 is a horizontal sectional view through the stem of the swinging frame of the wringer, showing the means for locking the frame in different positions.

Figure 4 is a perspective view of the cam sleeve, removed.

Figure 5 is a vertical sectional detail view through the gearing.

Referring particularly to the accompanying drawing, 10 represents a portion of a

washing machine tub and frame, in the lower portion of which is mounted the motor 11, for driving the transverse shaft 12, said shaft being mounted on the lower portion of the frame and projecting to a short distance therebeyond, where it is provided with a bevel gear 13. Extending outwardly from the upper portion of the washing machine frame 10, and directly above the bevel gear 13, is a bracket 14, the same being suitably braced to the frame by means of the rods 15, similar rods 16 being connected to the housing 17, of the gear 13, and the tub frame 10. Extending between the housing 17 and the bracket 14, is a vertical shaft 18, the lower end of which enters the housing 17 and is provided with a bevel gear 19, which meshes with the gear 13. On the bracket 14 there is mounted a vertical tubular member 20, and supported on the upper end of this tubular member is a rectangular vertically disposed frame 21, through which the upper end of the upper section 18' of the shaft 18 is disposed. The lower end of the section 18' has fixed thereto a sleeve 22 in which are formed the opposite longitudinal slots 23, and slidably in these slots are the opposite ends of the flat pin 24, which is disposed transversely through the upper end of the main shaft portion 18, said main portion being disposed within the lower end of the sleeve. Fixed to one side of the frame 21 is the clothes wringer 25, the shaft 26, of the lower roller of which extends into the side of the frame 21, and is provided with a bevel gear 27. Secured on the shaft section 18' within the frame 21, is a sleeve 28, and formed on the upper and lower ends of the sleeve 28 are the clutch faces 29 and 30, adapted, when the sleeve and shaft section 18' are shifted to engage respectively with the clutch faces 31' and 32' of the gears 31 and 32 which are loosely carried by the shaft section 18', and constantly mesh with the gear 27. Formed on the intermediate portion of the sleeve 28 is a peripherally grooved collar 33, in which is engaged the fork 34 of the arm 35, which arm extends horizontally toward the adjacent side of the frame. By reason of the pin and slot connection between the sections 18 and 18', the section 18' may be moved up and down without interfering with the rotation or the driving action thereof by the shaft 18. Mounted in the lower portion of the frame 21 is a vertically disposed tube 36 which

has a cutaway portion including the vertical wall 37 and the inclined wall 38. At the ends of the inclined wall 38 are formed the recesses 39 and 40, and intermediate 5 these recesses is a neutral recess 41. Slidable through the upper and lower members of the frame 21, and passing through the tube 36, is a shaft 42, the upper end of said shaft being bent laterally, above the upper 10 member of the frame and provided with a hand grip 43. On the shaft 42, between the upper member of the frame 21, and the arm 35, through which arm the shaft extends and is secured, is a coil spring 44, which 15 normally urges the shaft downwardly, so that the sleeve 28 will be moved to engage the clutch face 30 with the clutch face 32' of the gear 32. To prevent this movement until desired, there is disposed in the shaft 20 42 a laterally extending pin 45 which is arranged to rest in one of the recesses 39, 40 or 41, to hold the clutch in operative or neutral position.

When the hand-grip is grasped and the 25 shaft 42 turned in one direction the pin 45 will ride up on the inclined wall 38, with the result that the shaft will be elevated, carrying with it the sleeve 28, and engaging the clutch face 29 with that of the gear 31, causing the gear 31 to drive the gear 27. When the shaft 42 is turned in the opposite direction the pin will ride down the wall 38, and seat in the recess 40, carrying the sleeve 28 down and engaging the clutch face 30 30 with the gear 32 so that the gear 32 will drive the gear 27 and turn the wringer in the opposite direction. When the pin 45 rests in the intermediate recess 41, the clutch faces 29 and 30 are out of engagement with 35 both gears 31 and 32, thus throwing the 40 wringer out of gear. Thus the rollers of the wringer may be driven in either direction.

Pivottally mounted on the tubular member 45 20 is a substantially Z-shaped lever 46, the outer horizontal portion of which forms a handle, while the other horizontal portion extends through an opening 47, in the member 20, in position to engage with the longitudinal ribs 48, formed on the hub portion 50 49, of the shaft 18. A spring 50 is engaged between the handle portion of the lever 46 and the depending finger 51, carried by the member 20, for urging the lever into engagement with the ribs 48. By grasping the 55

lever, and depressing the same, to disengage it from the ribs 48, the frame 21 and the wringer, may be rotated on the shaft 18, to any position toward and away from the tub, that is desired, and upon release of the 60 lever, the same will engage the ribs and maintain the said parts from swinging movement in either direction. Thus the wringer may be swung into and out of operative position with respect to the tub. 65

What is claimed is:

1. The combination with a support having a shaft provided with loosely rotatable gears, and a clutch shiftable into alternate engagement with the gears, of a cam mounted on the support, a shaft slidable and rotatable within the cam and having means engaging therewith for causing sliding of the shaft upon rotation thereof, and resilient means for urging the slidable shaft 70 into engagement with the cam, and locking means between the cam and shaft. 75

2. The combination with a support, a shaft in the support, and loose gears spaced on the shaft, of a cam element on the support, a clutch shiftable alternately into engagement with the gears, a shaft slidable and rotatable in the cam element and operatively connected with said clutch, said slidable shaft being movable longitudinally 80 by the cam element upon rotation of the slidable shaft, means for normally urging the slidable shaft slidably and into engagement with the cam element, and locking means between the cam and shaft. 85

3. The combination with a slidable clutch, of a slidable and rockable counter shaft adjacent the clutch and having operative connections therewith, a tube through which the counter shaft is slidable and rockable, 90 one end of the tube being formed with a cam face having spaced notches, a spring for urging the counter shaft and clutch in one direction, and a pin on the counter shaft 95 held in frictional engagement with the said cam face and operable thereon to move the counter shaft and clutch in the opposite direction upon rocking the counter shaft. 100

In testimony whereof, we affix our signatures, in the presence of two witnesses.
